DESK TRAY

William James Bargen, Waukegan, Ill.

Application March 24, 1953, Serial No. 24,186

Term of patent 14 years

(Cl. D74—5)

To all whom it may concern:

Be it known that I, William James Bargen, a citizen of the United States of America, residing at Waukegan, in the county of Lake, and State of Illinois, have invented a new, original, and ornamental Design for a Desk Tray, of which the following is a specification, reference being had to the accompanying drawings, forming a part thereof.

In the drawings:

Figure 1 is a perspective view from the front of a desk tray showing my new design.

Figure 2 is a perspective view of the same showing the side opposite from Fig. 1.

Figure 3 is a top plan view of the same.

Figure 4 is a sectional view of the same taken on the line 4—4 of Fig. 3.

Figure 5 is a rear elevational view of the same. Figure 6 is a bottom plan view of the same.

I claim:

The ornamental design for a desk tray, as shown.

WILLIAM JAMES BARGEN.
